William J. Britt, Jr.
by Ralph Taich

UNITED STATES PATENT OFFICE.

WILLIAM J. BRITT, JR., OF ST. LOUIS, MISSOURI, ASSIGNEE TO KILLARK ELECTRIC MANUFACTURING COMPANY, OF ST. LOUIS, MISSOURI, A CORPORATION OF MISSOURI.

FUSE.

1,110,478.

Specification of Letters Patent. Patented Sept. 15, 1914.

Application filed December 15, 1913. Serial No. 806,820.

To all whom it may concern:

Be it known that I, WILLIAM J. BRITT, Jr., a citizen of the United States, residing at the city of St. Louis, State of Missouri, have invented certain new and useful Improvements in Inclosed Fuses, of which the following is a specification, reference being had to the accompanying drawings, forming a part hereof, in which—

Figure 1 is an elevational view, partly in longitudinal section, of an inclosed fuse embodying my invention in preferred form; Fig. 2 is a longitudinal sectional view through the same taken approximately at right angles to the section shown in Fig. 1; Fig. 3 is a transverse sectional view on the lines 3—3, Figs. 1 and 2; Fig. 4 is a transverse sectional view on the line 4—4, Fig. 1; Fig. 5 is a fragmentary view, partly in longitudinal section, showing a slightly modified form of terminal or contact-blade securing-means; Fig. 6 is a similar view showing another slightly modified form of terminal or contact-blade securing-means; and Fig. 7 is a perspective view of a member of the contact-blade securing-means shown in Fig. 6.

This invention relates generally to electric safety fuses and, more particularly, to certain new and useful improvements in that class of electric safety fuses commonly known as inclosed or cartridge fuses.

Fuses of this class usually comprise a hollow shell or casing of fibrous or other analogous insulation material, end-caps or closures, terminal members or contact-blades extending longitudinally of the casing and projecting therefrom at its ends through the end-caps, a suitable fusible element or link suitably electrically connected to the contact-blades and bridging the space therebetween within the casing, the fusible element or link having a current carrying-capacity less than the current carrying-capacity of the contact-blades and being adapted to carry the current up to a certain rated amperage and to blow or fuse on an overload or increase of current, thereby protecting the electric circuit in which the fuse may be arranged or inserted, as will be well understood, and a filling of suitable non-conducting material, preferably in a pulverulent or finely divided state, the function of which is to dissipate the heat and provide minute paths or interstices for the

escape of the vapor or gases evolved upon the fusing or blowing of the fusible element. Heretofore, the blade-terminals and end-caps or closures of the casing have been secured within and upon the casing in various ways and by various means, but the members or parts of fuses so constructed are, so far as I am aware, more or less difficult of assemblage and more or less expensive to manufacture. Heretofore, also, so far as I am aware, the fusible element or link of such fuses has been in the form, one or the other, of a broad flat strip, a plurality of such strips extending parallel with each other, a single wire, or a plurality of such wires.

The objects of my present invention are to provide an efficient fuse of the class stated of simple and economical construction, of few readily assembled and renewable parts or members, and in which the terminal or contact-blades and their attached fusible link are operatively removably fastened and held within the fuse-casing by securing-means engaging merely with the casing and blades; to provide a fuse of the kind stated having a fusible link formed of main or principal and secondary fusible members, the secondary members being adapted normally to perform the function of leading-in or current-carrying means for the main fusible member and abnormally to perform the function of a safety valve for the fuse; and to improve, generally upon, and simplify the construction of, fuses of the class mentioned.

With the above and other objects in view, my invention resides in certain novel features of form, construction, arrangement, and combination of parts, all as will herein-after be described and afterward pointed out in the claims.

In the accompanying drawings, in which like reference characters refer to like parts throughout the several views, 1 indicates the fuse casing, which is preferably an open-ended tubular shell of fibrous or other analogous insulation material and which may be of any suitable length and diameter as required according to the desired size or current-carrying capacity of the fuse.

2—2 indicate suitable flanged or cup-shaped preferably metallic caps which are adapted, in the finished fuse, to fit on casing 1 at its opposite ends and provided closures therefor, caps 2—2 being removably secured on casing 1 by means of small screws 110.

or other like fastening means 3, as seen particularly in Fig. 2.

4 indicates what I will call the main member of the fusible element or link of my new fuse, this member 4 being preferably, as seen particularly in Fig. 2, in the form of a plurality of separated wires of zinc or other suitable readily fusible metal stretched lengthwise of, and within, casing 1 tightly between, and having their opposite ends suitably electrically connected to, the inner ends of, what I will designate, the secondary members 5—5 of the fusible element or link of the fuse.

15 Members 5—5, which are both preferably in the form of broad flat strips also of zinc or other suitable readily fusible metal having the same melting point as, but having a larger or greater ampere carrying-capacity than, main member 4 of the fuse, are preferably riveted or otherwise suitably electrically connected at their opposite ends to the inner ends of oppositely-disposed relatively thick, heavy, preferably flat fuse terminal-members or contact-blades 6—6 of copper or other suitable conducting material. Blades 6—6 also extend lengthwise of casing 1 and at their outer ends project outwardly in the finished fuse through suitable elongated or 30 rectangular slots in the face of end caps 2—2 and thereby form or provide contact-terminals for the fuse, being readily engaged with knife-blade contacts or the like.

Adjacent each of its ends, casing 1 is provided with a pair of diametrically opposite or alining openings or perforations, as at 1^a, preferably at right angles to the openings provided for cap-securing screws 3; and extending at right angles to, and bearing at 40 their inner ends on, the opposite broad flat faces of blades 6—6, are pairs of small tubular members 7—7 preferably of equal length for properly longitudinally centering blades 6—6 and their attached fusible element or 45 link formed of said members 4 and 5 in casing 1, members 7—7 at their outer ends tightly, but removably, fitting in a pair of said openings 1^a and thereby engaging with casing 1, as seen clearly in Figs. 1 and 3. 50 Loosely, that is to say, removably, fitting lengthwise in each of said pairs of members 7 and extending transversely of casing 1 and through blades 6—6 at right angles to the broad faces thereof are pins or members 55 8—8 for removably securing blades 6—6 and their attached fusible element formed of said members 4 and 5 in proper operative position lengthwise of casing 1, each of said pins 8 preferably having a length approximately the same as the outer diameter of casing 1, as also seen clearly in Figs. 1 and 3. The flanges of caps 2—2 being of sufficient length to extend inwardly beyond said openings 1^a, as seen clearly in Figs. 1 and 2, it 65 will be evident not only that said openings

1^a will be completely covered, but also that said tubular members 7 and pins 8 will be firmly and positively held against removal in their described blade-securing position. Preferably also the outer ends of members 7 70 are approximately flush with the periphery of casing 1.

Surrounding the fusible element or link formed of said members 4 and 5 and filling the interior of casing 1, as a filling 9 of any suitable non-conducting material preferably in a pulverulent or finely divided state, such as pulverized plaster of Paris or slaked lime, adapted to dissipate the heat and provide minute paths or interstices for the escape of 80 the vapor or gases arising or evolved upon the fusing or blowing of the fusible element or link, caps 2—2, which are, as is usual, preferably provided with suitable vent perforations or openings 10—10, being firmly 85 held by screws 3 upon casing 1 and prevented thereby from being blown off casing 1 by the expansion of the gases generated on the fusing of said link.

In assembling the parts or members of 90 my new fuse, blades 6—6 and their attached fusible members 4 and 5 forming the fusible element or link are lengthwise inserted into casing 1, when blade-securing pins 8 are fitted transversely of casing 1 and through, 95 and at right angles to the broad faces of, blades 6—6, the ends of pins 8—8 being now temporarily held by the operator's fingers or other means substantially flush with the periphery of casing 1. Centering members 100 7—7 are then slidably fitted upon pins 8 to longitudinally center blades 6—6 and their attached fusible link in casing 1. Filling 9 and end caps 2—2 are now, as described, operatively placed within and secured upon casing 1, when the fuse is ready 105 for marketing. It will be observed that caps 2—2, in addition to holding the blade-securing means in relatively fixed position, also prevent any pivotal or sidewise movement of blades 6—6 relatively to casing 1. 110 To renew or replace any part or member of the fuse, it is merely necessary to remove end caps 2—2, when the remaining members of the fuse may be readily taken from casing 115 1, as will be obvious.

In use, on a normal increase of current over the rated carrying-capacity of the fusible wires 4, but less than the rated carrying-capacity of fusible members 5, said wires 4 120 will blow or fuse and thereby protect the circuit in which the fuse may be inserted. Should there, however, be an extreme overload of current or an increase of current over the rated carrying-capacity of fusible 125 members 5, then, in addition to wires 4 fusing or blowing, the said secondary fusible members 5 will also blow or fuse and thereby prevent the arc caused or created under such abnormal conditions from disrupting 130

the fuse, the said secondary fusible members 5 acting, so to speak, under such conditions, as a safety valve for the fuse and having the function normally merely of leading-in 5 or current-carrying strips for the wires or principal fusible members 4.

In Fig. 5, I have shown a slightly modified form of blade-securing means, in that, instead of having a plurality of tubular 10 blade-centering members 7 separable from pin 8, as hereinbefore described, the pin member 11 is integral with, and forms a reduced extension of, a cylindrical blade-centering member 12 usable in lieu of one of 15 said separable centering members 7, the fuse being otherwise similar to that shown in Figs. 1 and 4, inclusive.

In Fig. 6, the blade-securing means shown is greatly similar to the blade-securing 20 means shown in Fig. 5, but differs therefrom in that the pin member 13, which is integral with, and forms a reduced extension of, cylindrical blade-centering member 14, is threaded for receiving the coöperating 25 blade-centering member 15. In this form also, instead of the secondary fusible members 5 being directly riveted to blade 6, as seen in Figs. 1 and 2, the secondary fusible member 16 shown is lengthened and per- 30 forated to receive pin member 13, blade-centering member 15, on being threaded upon pin member 13, firmly holding member 16 and blade 6 in electrical contact.

My new fuse may be economically manu- 35 factured, and it will be observed that the several parts thereof may be readily assembled and may also be easily and conveniently renewed or replaced. It is to be understood that changes in the form, con- 40 struction, arrangement, and combination of the several parts of the fuse may, within the scope of the appended claims, be made and substituted for those herein shown and de- 45 scribed without departing from the nature and principle of my invention.

Having thus described my invention, what I claim and desire to secure by Letters Patent is:

1. In a renewable fuse of the class stated, 50 the combination with a tubular casing open at its end, said casing being provided adjacent its end with a pair of diametrically opposite openings, of a terminal-blade operatively disposed lengthwise partly interiorly 55 and exteriorly of said casing and adapted for electrical connection interiorly of said casing with a fusible member, said blade being transversely provided with a perforation, a blade-securing pin detachably secur- 60 ing said blade and casing in coöperative re- 65 lation, said pin extending loosely through said perforation and removably projecting at its ends into said openings and thereby removably engaging with said blade and 70 casing, and a slotted end-cap removably

fitting on the end of said casing over the projecting portion of said blade, said cap providing a removable closure for the end of the casing and removably holding said pin in its said blade-securing position; sub- 75 stantially as described.

2. In a renewable fuse of the class stated, the combination with a tubular casing open at its end, said casing being provided adjacent its end with a pair of diametrically opposite openings, of a terminal-blade having relatively broad flat opposite faces op- 75 eratively disposed lengthwise partly interiorly and exteriorly of said casing and adapt- 80 ed for electrical connection interiorly of said casing with a fusible member, said blade being transversely provided with a perforation at right angles to the said faces thereof, a blade-securing pin detachably se- 85 curing said blade and casing in coöperative relation, said pin extending loosely through said perforation and removably projecting at its ends into said openings and thereby removably engaging with said blade and 90 casing, and a slotted end-cap removable fit- 95 ting on the end of said casing over the projecting portion of said blade, said cap providing a removable closure for the end of the casing and removably holding said pin in its said blade-securing position; substan- 100 tially as described.

3. In a renewable fuse of the class stated, the combination with a tubular casing open at its end, said casing being provided adjacent its end with a pair of diametrically opposite openings, of a terminal-blade having relatively broad flat opposite faces op- 105 eratively disposed lengthwise partly interiorly and exteriorly of said casing and adapt- 110 ed for electrical connection interiorly of said casing with a fusible member, said blade being transversely provided with a perforation at right angles to the said faces thereof, a blade-securing pin detachably se- 115 curing said blade and casing in coöperative relation, said pin extending loosely through said perforation and removably projecting at its ends into said openings and thereby removably engaging with said blade and 120 casing, means engaging said blade and cas- 125 ing for centering said blade longitudinally of said casing, and a flanged slotted end- 130 cap removably fitting on the end of the cas- ing over the projecting portion of said blade, said cap providing a removable closure for the end of the casing and removably holding said pin in its said blade-securing position; substantially as described.

4. In a fuse of the class stated, a tubular casing provided adjacent its end with a pair of diametrically opposite openings, a ter- 135 minal-blade having relatively broad flat op- 140 posite faces, said blade being transversely provided with a perforation at right angles to the said faces thereof, a blade-securing 145

pin extending loosely through said perforation and removably projecting at its ends into said openings, blade-centering members having their inner ends bearing upon the flat faces of said blade and their outer ends removably projecting into said openings and thereby engaging with the wall of said casing, and means on the casing for removably holding said pin and blade-centering means in operative position; substantially as described.

5. In a fuse of the class stated, a tubular casing provided adjacent its end with a pair of diametrically opposite openings, a terminal-blade having relatively broad flat opposite faces, said blade being transversely provided with a perforation at right angles to the said faces thereof, a blade-securing pin extending loosely through said perforation and removably projecting at its ends into said openings, tubular blade-centering members loosely fitting on said pin on opposite sides of said blade, said members having their inner ends bearing upon the flat faces of said blade and their outer ends removably projecting into said openings and thereby engaging with the wall of said casing; and means on the casing for removably holding said pin and blade-centering means in operative position; substantially as described.

6. In a fuse of the class stated, a tubular casing provided adjacent its end with a pair of diametrically opposite openings, a terminal-blade having relatively broad flat opposite faces, said blade being transversely provided with a perforation at right angles to the said faces thereof, a blade-securing pin extending loosely through said perforation and removably projecting at its ends into said openings, tubular blade-centering members loosely fitting on said pin on opposite sides of said blade, said members having their inner ends bearing upon the flat faces of said blade and their outer ends removably projecting into said openings and thereby engaging with the wall of said casing, and a flanged end-cap on said casing for removably holding said pin and blade-centering means in operative position; substantially as described.

7. In a fuse of the class stated, a tubular casing provided adjacent its end with a pair

of diametrically opposite openings, a terminal-blade having relatively broad flat opposite faces, said blade being transversely provided with a perforation at right angles to the said faces thereof, a blade-secur ing pin 55 extending loosely through said perforation and removably projecting at its ends into 60 said openings, tubular blade-centering members loosely fitting on said pin on opposite sides of said blade, said members having their inner ends bearing upon the flat faces of said blade and their outer ends removably 65 projecting into said openings and thereby engaging with the wall of said casing, and a slotted end-cap on said casing for removably holding said pin and blade-centering members in operative position and for preventing pivotal movement of said blade relatively to the casing, said blade having a portion projecting through the slot of said 70 cap; substantially as described.

8. In a renewable fuse of the class described, the combination with a tubular casing open at its ends, said casing being provided adjacent its ends with pairs of diametrically opposite openings, of a pair of oppositely-disposed terminal blades extending lengthwise, and partly interiorly and exteriorly, of said casing, each of said blades being transversely provided with a perforation, blade-securing pins detachably securing said blades and casing in co-operative relation, said pins extending loosely through said perforations and removably projecting at their ends into said openings, a renewable fusible element disposed lengthwise of and entirely within said casing, said fusible element having electrical connection at its ends with the inner ends of said blades, and slotted end-caps removably fitting on the ends of said casing over the projecting portions of said blades, said caps providing removable closures for the ends of the casing and removably holding said pins in their said blade-securing position; substantially as described. 75 80 85 90 95

In testimony whereof, I have signed my name to this specification, in the presence of two subscribing witnesses.

WILLIAM J. BRITT, Jr.
